UNITED STATES PATENT OFFICE

2,632,409

LATCH FOR FLOOR RACKS

Reuben Francis Nelson and Henry Daniel
Doerman, Roseville, Calif.

Application March 11, 1949, Serial No. 80,944

2 Claims. (Cl. 105—375)

1

This invention relates to a latch for floor racks and more particularly to a latch mechanism for use in refrigerator cars to hold the floor rack in raised position during cleaning of the car.

In refrigerator cars it is customary to provide floor racks formed of rack sections which are hinged at the side of the car to swing between a horizontal position adjacent the car floor during use and a vertical position adjacent the car side wall to facilitate cleaning of the car. The present invention relates specifically to a latch mechanism to hold the floor rack sections in vertical position without interfering with normal use of the car.

It is one of the objects of the invention to provide a latch which is extremely simple to manufacture and install and which positively holds the floor rack sections in elevated or raised position with a minimum liability of accidental release.

Another object is to provide a latch which is fully recessed in the car side wall when not in use to provide a smooth continuous wall so that there will be no interference with lading in the car and no liability of damage to the latch.

The above and other objects and advantages of the invention will be more readily apparent when read in connection with the accompanying drawing, in which—

Figure 1 is a diagrammatic transverse section through a refrigerator car equipped with a latch according to the present invention;

Figure 2 is an enlarged partial perspective view showing the latch in use;

Figure 3 is a view similar to Figure 2 showing the condition of the latch when not in use;

Figure 4 is a perspective view of the latch mechanism;

Figure 5 is a section with the parts in the position of Figure 2; and

Figure 6 is a section with the latch in the position of Figure 3.

The invention may be applied to any standard or conventional car construction having a floor 10 and vertical side walls 11. It will be understood that the floor and side walls may be of conventional double wall insulated construction of any desired type and are illustrated only diagrammatically. The floor of the car carries floor racks formed by a plurality of rack sections 12, each of which is formed by supporting beams 13 extending longitudinally of the car and connected by slats 14 extending across the car. Each of the rack sections is hinged adjacent the side wall of the car, as indicated at 15 so that it can be swung

from a horizontal position, as indicated at the left in Figure 1, to a vertical position adjacent the side wall of the car, as indicated at the right in Figure 1.

According to the present invention, a latch is provided to hold the floor rack sections in their vertical positions to facilitate cleaning of the car. As shown, the car side wall 11 is recessed, as indicated at 16, to provide a space in which the latch itself may be mounted, and the latch itself is constructed to fit into the recess so that the latch and car wall will present a substantially smooth continuous surface.

With this construction there is no interference with the lading in the car, and liability of damage to the latch is eliminated.

The latch itself comprises a pair of flat metal plates 17 and 18, each of which is rolled over at one edge, as indicated at 19 and 21. A hinge pin or pintle extends through the rolled over portions 19 and 21 to form an offset hinge connection between the plates. With this construction the plates can be swung from a spaced parallel position, as shown in Figures 3 and 6, to a position substantially at right angles to each other, as shown in Figures 2 and 5. The backplate 17 is flat and is formed with a series of openings to receive fastenings such as screws 23 by means of which it is secured to the back wall of the recess. It will be noted, as best seen in Figure 6, that the distance between the plates when they are in their spaced parallel position is equal to the depth of the recess so that the outer surface of the plate 18 is flush with the inner surface of the car side wall 11. Thus the plate 18 forms, in effect, a continuation of the car side wall surface so that there is no interference in the lading in the car and there are no projecting parts on the latch mechanism to be caught by the lading and damaged.

At its free edge the plate 18 is turned over into a flange 24 which terminates in an inwardly extending lip 25. The flange and lip project from the plate 18 a distance equal to the hinge offset so that when the latch is in the positions shown in Figures 3 and 6 the lip 25 will engage the inner wall of the recess and will limit swinging of the plate 18 into the recess. This insures that the plate 18 will be held in the plane of the car wall to provide a smooth surface. The flange 24 and lip 25 also form a hook member to engage the upper edge of the floor rack when it is in its raised position to hold it in this position. To facilitate raising of the latch plate 18, it is preferably cut or notched at its edges, as indicated

2

at 26, to provide finger openings by which the plate may be gripped and swung outward easily.

The edge portion of the floor rack which is engaged by the latch preferably carries a complementary latch plate 28 which may be secured to the outermost beam 13 by bolts 29 or the like. The plate 28 has an angular flange 31 to underlie the slats 14 adjacent the edge thereof and terminates in an outwardly projecting lip 32. When the latch is engaged, as shown in Figures 2 and 5, the flanges 24 and 31 and the lips 25 and 32 will interengage securely to hold the rack in its elevated position. Due to the presence of the lips 25 and 32, the latch cannot be accidentally disengaged but requires for disengagement that the floor rack be pressed tightly against the side wall of the car and that the latch plate 18 be deliberately raised to free the flange 24 from the flange 31 and to clear the end of the slats 14.

It will be observed that the latch of the present invention is very simple to manufacture and install and that it provides a positive latching action securely to hold the floor racks elevated. At the same time it is extremely easy to use and avoids any interference with the car lading.

While one embodiment of the invention has been shown and described in detail herein, it will be understood that this is illustrative only and is not to be taken as a definition of the scope 30 of the invention, reference being had for this purpose to the appended claims.

What is claimed is:

1. A latch for floor racks and the like comprising a pair of plates having flat rectangular body portions pivotally interconnected at one edge to swing from an overlying parallel position to a position at substantially a right angle to

each other, one of the plates being bent over at its free edge to form a hook portion to engage a floor rack, and the other plate having a flat surface for connection to a wall, and a complementary angular plate for attachment to the floor rack having an edge portion to interengage with the bent over edge of said one of the plates.

2. A latch for floor racks and the like comprising a pair of plates having flat rectangular body portions pivotally interconnected at one edge to swing from an overlying parallel position to a position at substantially a right angle to each other, one of the plates having a flange at its free edge turned toward the other plate when the plates are in their overlying parallel position and formed with an inwardly turned lip at its edge to define a hook portion to engage a floor rack, and a complementary plate for attachment to the floor rack having a flat edge portion terminating in an outwardly turned lip to interfit with the flange and lip on said one of the plates.

REUBEN FRANCIS NELSON.
HENRY DANIEL DOERMAN.
